UNITED STATES PATENT OFFICE.

JOE OTIS LEE, OF GREENVILLE, MISSISSIPPI.

BOILER-LUBRICATOR.

1,185,808.

Specification of Letters Patent. Patented June 6, 1916.

Application filed October 1, 1914. Serial No. 864,496.

To all whom it may concern:

Be it known that I, JOE OTIS LEE, a citizen of the United States, residing at Greenville, in the county of Washington and 5 State of Mississippi, have invented a new and useful Boiler-Lubricator, of which the following is a specification.

The present invention relates to improvements in a boiler lubricator, one object of 10 the present invention, being the provision of a lubricant supplying device adapted to be interposed between the injector and the boiler, whereby the effect of the injector in forcing or pumping water to the boiler, 15 will draw from the present lubricator a certain amount of lubricant so that incrustation of the boiler is prevented and at the same time, a sufficient amount of oil is supplied to the upper surface of the water to 20 prevent foaming and boiling over.

A further object of the present invention, is the provision of a simple, inexpensive and easily installed device of this character, which is readily attached between the 25 injector and the boiler, to properly supply the lubricant thereto, and in sufficient quantities to produce the desired result and permit of the use in the boiler of hard water without 30 bad effect upon the boiler.

With the foregoing and other objects in view which will appear as the description proceeds, the invention resides in the combination and arrangement of parts and in the details of construction hereinafter 35 described and claimed, it being understood that changes in the precise embodiment of the invention herein disclosed can be made within the scope of what is claimed without departing from the spirit of the invention.

40 In the drawings is illustrated the present lubricator, the oil receptacle being shown in longitudinal section, while the check valves in the pipe leading from the injector to the boiler are also shown in section.

45 Referring to the drawings, the numeral 1 designates the oil receptacle, which is a cylindrical member, adapted to be disposed horizontally, there being attached at one end thereof, the two nipples or pipes 2 and 50 3, which have interposed therebetween, the sight glass 4, so that the level of the contents within the receptacle 1 may be readily discerned.

A valved pipe 5 is connected to the 55 reservoir 1 so that the cup 6 which is car-

ried thereby will constitute a means for directing the lubricant into the receptacle 1 when filling the receptacle, a valved pipe 7 being also connected to the tank 1 so as to permit of the venting of the tank during 60 the filling operation.

Leading from the tank 1 is a pipe 8, which has interposed therein a manually controlled valve 9, said pipe 8 being in communication with the pipe 10, which as indicated is interposed between the injector and the boiler, indicated by such words upon the drawings. Connected in the pipe 10 is the check valve 12, adjacent the connection thereof to the injector, while at the 70 opposite end is the check valve 13, such valves being so arranged that the flow of water through the check valve 12 will be permitted toward the boiler, but will be prevented from the opposite direction, while 75 the check valve 13 will permit the flow of water to the boiler but not toward the connection of the pipe 8 to the pipe 10. It will thus be seen that the tendency of the flow of water through the pipe 10 will produce 80 a vacuum within the pipe 8 and thus cause the lubricant within the tank 1 to be withdrawn and be carried by the water to the boiler.

It is intended that the present device may 85 be connected for use with a battery of boilers or with a single boiler as may be found expedient, and that the tank 1 be of sufficient size to supply the necessary quantity for this purpose.

90 Connected to the under side of the tank 1 is a valved outlet 14 so that the tank may be properly emptied when found desirable.

It has been proven in practice with the present device, that the entire surface of 95 the water within the boiler will be covered by the lubricant and thus will stop the water from foaming, and thus relieve the boiler of a great danger, for it has been found where soft or foaming water is used, that 100 the water column often indicates the boiler full of water when it is dry, thus resulting in damage to the tubes due to the heat thereon and in many cases will be the cause of an explosion when the water is permitted to 105 enter the boiler.

The present device can also be used for injecting compounds in the boiler but is more especially designed for injecting lubricant in sufficient quantities to cover the up- 110

per surface of the water within the boiler, although the present device will also prevent incrustation or scaling of the tubes.

When the valves 5 and 7 are open, during 5 the filling operation, and when the valve 9 is closed, a portion of the lubricant from the receptacle 1 is trapped in the horizontal pipe 10 between the valves 12 and 13. The valve 12 prevents the lubricant thus trapped from 10 flowing backwardly into the injector line when the pressure is off the injector line or when the same is empty.

What is claimed is:

In a device of the class described, a receptacle 15 provided with a valve controlled filling opening and with a valve controlled vent; a vertical pipe communicating with the top of the receptacle; a cut off valve in the pipe; a horizontal pipe communicating intermediate its ends with the vertical pipe; and

check valves in the horizontal pipe on opposite sides of the vertical pipe, the horizontal pipe being adapted to constitute a part of an injector line to a boiler, the cut off valve being adapted to be closed, and the check valves being adapted to close automatically, when there is no flow through the horizontal pipe, thereby to trap a portion of the lubricant discharged from the receptacle in the horizontal pipe and in the upper portion of 25 the vertical pipe, when the vent and the filling opening are in use.

In testimony that I claim the foregoing as my own, I have hereto affixed my signature in the presence of two witnesses.

JOE OTIS LEE.
